CHARLES P. STEWART, OF LOS ANGELES, CALIFORNIA

ULTRA-VIOLET RAY TRANSMITTING MATERIAL

Application filed December 18, 1929, Serial No. 415,094. Renewed January 21, 1933.

This invention or discovery relates to an ultra-violet ray transmitting material. I have discovered that when the shell of a shell fish, known as *Placuna Placenta* which is found near the Philippine Islands and commonly known in such localities as Kapa, is thoroughly cleaned that this shell has peculiar properties which are quite advantageous in that the material has the ability of transmitting ultra-violet rays.

It is, therefore, an object of this invention to provide an improved ultra-violet ray transmitting material having the advantages developed from such discovery. The improved material is highly advantageous in that it not only is capable of transmitting a large portion of ultra-violet rays but also it has the advantage of being weather resistant, thus enabling windows or panels to be formed of the material for sun porch purposes and the like wherein the panels or windows are subject to weather.

With the foregoing and other objects in view, which will be made manifest in the following detailed description, and specifically pointed out in the appended claims, reference is had to the accompanying drawing for an illustrative embodiment of the invention, wherein:

30 Fig. 1 is a plan view of one of the shells, illustrated as having been cleaned and ready to be cut into a section of suitable form enabling the sections to be combined together in forming a window panel or the like.

35 Fig. 2 is a plan view of one of the sections cut from a shell.

Fig. 3 is a partial view in elevation of a window panel made up of shell sections.

Fig. 4 is a partial view in plan illustrating 40 how the sections may be mounted in forming a roof or the like.

Fig. 5 is a sectional view taken through a portion of the roof shown in Fig. 4.

Referring to the accompanying drawing, 45 wherein similar reference characters designate similar parts throughout, I take shells of the *Placuna Placenta* variety of shell fish, commonly found in the Philippine Islands and known in such localities as Kapa. One 50 of such shells is indicated at 10 on Fig. 1.

This shell fish has shells which are highly suitable for my purposes in that one shell of the shell fish is substantially flat, the other shell is usually concavo-convex to a greater or less degree. I prefer to employ only the flat shells for my purposes although the concavo-convex shells may be employed in forming curved or domed shape panel structures. These shells are cleaned by scraping and are preferably brushed thoroughly with a solution of acid. I find a 10% solution of hydro-chloric acid or of nitric acid suitable for these purposes. The resulting shell structure is substantially flat and may be of the approximate appearance as shown in Fig. 1. It is translucent, allowing light to pass therethrough, but preventing images to be clearly transmitted unless the objects producing the image are located directly against one side of the shell. The shell is quite thin, being one-sixteenth of an inch or thinner in thickness, and has a laminated structure. The laminations I find cause the shell to be quite strong, being materially stronger than ordinary window glass.

I cut the shell, when it is thus thoroughly cleaned, into a regular shape, such shape being indicated by dotted lines upon Fig. 1, and in this manner a section, indicated at 11 in Fig. 2, is produced. The section which I have illustrated is rectangular in form but it will be readily understood that other suitable shapes such as triangles, hexagons, diamonds, and the like, may be adopted if desired. In making a suitable window panel, as shown in Fig. 3, a plurality of these sections 11 are assembled together in end to end relation, preferably with staggered joints. The sections are connected together by leading 12 so that the completed panel is constructed in a manner quite similar to that in which stained glass windows have been manufactured heretofore.

In erecting a section of roofing I preferably employ suitable supports indicated at 13 which are connected at intervals by cross members 14. On the supports sheet metal members 15 are positioned which extend upwardly from the flanges 16 and are reversely bent at their upper ends and have flanges

17. Likewise sheet metal members 18, which are reversely bent at their longitudinal center lines and which provide at their bases flanges 19, are supported on the cross members 14. The sections 11 are positioned on the flanges 17 and 19 with overlapping edges so that the sections are positioned in a manner quite similar to that in positioning shingles in the conventional manner. Inverted channel strips are then provided which are filled with putty or similar material and these channel strips are forced downwardly over the tops of the sheet metal members 18 toward the sections 11. The putty is thus pressed against the sections 11, holding them in place and forming a weather proof joint. These channel strips may be held in position by suitable fastening elements indicated at 21, which are extended laterally through apertures in the channel strips and in the sheet metal members 18. The ends of these fastening elements may be cut off when the roof is completed.

25 The improved window panel or roofing structure is highly advantageous in its ability to transmit ultra-violet rays and its ability to withstand weather. I have procured results of a test of this material for transmitting ultra-violet rays in comparison with other materials known to have similar properties. A quartz plate has the ability of transmitting ultra-violet rays having wave lengths down to roughly 2537A degrees. A compound now on the market under the trade name of "Corex" has the ability of transmitting ultra-violet rays to nearly the same extent. The product of my discovery and invention is capable of transmitting ultra-violet rays down through 3021A degrees. As compared with thin plate glass, such glass is only capable of transmitting such waves having a wave length down to approximately 4100A degrees. Ordinarily a quartz plate cannot be used for my purposes because of the expense involved. I find that "Corex" is unsuitable for my purposes because of its inability to withstand weathering. When subjected to weather the "Corex" in the course of time

turns white and because of this I find that its ability to transmit ultra-violet rays is practically lost. Insofar as I am aware my material is in no way affected by the weather. By virtue of the fact that ultra-violet rays present in solar radiation do not extend below 2900A degrees, due to the absorption of the earth's atmosphere, it will be appreciated that my material is capable of transmitting all the ultra-violet rays available at the earth's surface which are present in solar radiation.

From the above described discovery and constructions it will be readily apparent that an improved material has been developed which is highly advantageous for the purpose of transmitting ultra-violet rays. The material can be relatively cheaply produced as these shells are relatively abundant in the localities in which they are found. The thickness of the shell may be reduced by continued scraping and cleaning with acids so that practically any thickness of the sections 11 can be obtained. The improved material is relatively strong and is quite suitable for sun porch purposes and the like in that it transmits day light by virtue of its translucent character and it will not transmit images of persons taking sun baths on the sun porch. The ability to withstand the weather and the ability to transmit practically all of the ultra-violet rays present in sun light at the earth's surface I consider as being the most important advantages present in the new material.

Various changes may be made in the details of construction without departing from the spirit or scope of the invention as defined by the appended claims.

I claim:

1. The method of transmitting ultra-violet rays which comprises placing cleaned Placuna Placenta shell between a source of such rays and the place where the rays are desired.
2. A window for transmitting ultra-violet rays comprising a frame and clean light transmitting Placuna Placenta shell in the frame.

CHARLES P. STEWART. 115
